UNITED STATES PATENT OFFICE.

ADRIEN C. BECKERT, OF LOS ANGELES, CALIFORNIA.

ADJUSTABLE DRY-DOCK.

1,372,394.

Specification of Letters Patent. Patented Mar. 22, 1921.

Application filed February 25, 1920. Serial No. 361,334.

To all whom it may concern:

Be it known that I, ADRIEN C. BECKERT, a citizen of the United States, residing at Los Angeles, in the county of Los Angeles and State of California, have invented new and useful Improvements in Adjustable Dry-Docks, of which the following is a specification.

This invention relates to docks and more particularly to marine dry docks, and has for its object to provide a floating dry dock constructed so as to be capable to accommodate vessels of different beams, and further to provide a floating dock formed of a plurality of independent co-operative units each forming one side of a dock, and also to provide for the ready disconnection, removal and replacement of any of the separate pontoons of which the floating apparatus is constructed; the invention consisting of the construction and details shown in the accompanying drawings and described and claimed hereinafter.

Figure 1 is a plan view of the assembled units, parts being broken away for the purpose of clearness to show details of construction.

Fig. 2 is a side elevation of the dock shown as supporting a vessel and being partly broken away.

Fig. 3 is a detail sectional view on line 3—3 of Fig. 1.

Fig. 4 is an end elevation, partly broken away, of a float and showing its use in supporting a vessel.

Fig. 5 is a detail view in section on line 5—5 of Fig. 1.

The improved floating dry dock is constructed of a pair of co-operative unit structures each of which consists of a series of tanks or pontoons, those of one series and unit being designated at A in Fig. 1 and those of the opposite unit being designated at B. These units may be of any suitable form of construction, shape and size and are shown as, generally, cylindrical with hemispherical ends, all of the pontoons of one series as A being arranged parallel to each other in suitable spaced relation and connected at their ends by detaching means in the form of chains 2 to the bridge work or deck structure; the deck structure of each unit comprising a pair of parallel girders 3—3 forming saddles with seats 3^a formed in their lower edges and upwardly into which the respective pontoons will float and

bear in the construction and assemblage, or mounting of the apparatus.

The longitudinally extending saddle beams 3—3 of a unit are suitably transversely connected as by ties 4, and upon this deck structure, of each unit, is built up a shore wall or dock side, the shore wall including a suitable form of stepped shoulders or surfaces 6 rigidly supported and built upon the framework 5 which is, preferably, constructed to one side of the deck structure, so that when the two units are assembled by the telescopic arrangement of the spaced pontoons A and B of the respective units there will be formed between the superstructure a ship receiving way in which a ship S can be shored up as by the shores or braces indicated at T.

To support the ship, each of the pontoons is preferably provided with one or more keel blocks 8 of such height as, preferably, to project up above the transverse tie members 4 of the units, so that when the dock structure is previously submerged to the requisite depth to be floated under the ship to be raised then upon the compression of air into the several pontoons and the displacement of the water, with the upward movement of the pontoons and deck structure, the keel blocks 8 will come into contact with the keel of the vessel and thereafter the load of the vessel will be taken directly by the pontoon structures through means of the keel blocks 8.

It is desirable to provide for the relative transverse adjustment of the units so as to accommodate vessels of different beam, and to accomplish this with facility certain transverse members 4 of the pontoon system A, for instance, can be provided with a tooth or rack member or surface 10 of suitable length, and this is designed to engage with a screw or other complementary medium 11, here shown as formed or mounted on the end of a respective shaft 12 a series of which is provided, as may be required; and all of the shafts extend transversely with respect to the unit and have pinions 13 at one end, these pinions engaging respective gears 14 that are secured on a longitudinally extending shaft 15, Figs. 1 and 2, on a suitable point at which there is secured a driving pinion 16 engaging a complementary pinion 17 that is secured on the lower end of a shaft 18, in this case, extending upwardly through suitable bearings and having on its upper

end a gear 19 meshing with a gear 20 secured on the end of a jack shaft 21, Fig. 1. This shaft has a gear 22 fixed thereon and this gear is in constant mesh with a pair of 5 reverse gears 23 and 24 that are loosely mounted on a shaft of an engine 25. The engine is mounted in any suitable and convenient position on the superstructure of a unit, as for instance beneath the overhanging 10 ¹⁰ side or shoring wall.

To secure the operation of this gearing and effect the turning of the adjusting worms or screws 11 and thus cause the relative shift of the units as to each other, a 15 suitable clutch device is mounted on the shaft of the engine 25 and indicated at 26, the throwing of this clutch in one direction locking the gear 23 to the engine shaft and thus driving the jack shaft 21 in one direction. Conversely, the throwing of the 20 clutch 26 in the opposite direction will interlock the driving pinion 24 with the gear 22 and the shaft 21 will be reversed.

While the one shifting mechanism may be 25 serviceable to secure the relative lateral adjustment or movement of the dock units, it is preferred that each of these units be provided with its own pneumatic system for compressing air into the respective pontoons 30 A—A or B—B and to that end a motor 25 is mounted on each of the units and is adapted to operate an air compressor C, a clutch 30 being interposed between the engine and the compressor so that the latter can be operated at will or disconnected from the engine.

To secure the submersion of the float or to enable the latter to be shifted in under 40 a vessel to be raised, each of the air compressors of the units is connected as by a main air pipe 31 to a distributing air pipe 32, the air pipe 31, preferably, being provided with a blow-off valve 33 which when 45 opened will permit of the exhaust of air as water will flow into the pontoons of the unit when the water valve 34 of each section of the pontoon, when the pontoon is provided with sections as is preferred, is open.

To elevate the float the valve 33 is closed, 50 the water valves 34 of the respective unit opened, and the compressor operated so that compressed air will flow through branches 35 thereof, each of these branches being connected as by another branch 36 to the 55 respective compartments of the several pontoons. The compressing of the air will discharge the water from the compartments of the pontoons whereupon valves 37 of the compartments at the head of the branches 60 36 can be closed so as to retain the air pressure on each of the compartments.

It will be understood that after the pontoons have been filled to the desired degree with water by the outlet of the air from the 65 compartments as by the opening of the local

valves 37 or the main blow-off valve 33 that the immersed dock will be shifted to a position under the vessel to be raised and then the main blow-off valve closed, and also the sea or water valves will be opened by the 70 turning of the handwheels 34 thereof and air will be pumped into the pontoons to the desired degree of pressure so that the water will be expelled, with the result that the pontoons will press upwardly against the 75 superstructure and the keel blocks 8 be shifted up against the keel of the vessel and the load thereof taken up; and further upward movement of the dock will cause the vessel to be lifted to the desired degree, and so if necessary entirely above the surface of the water.

From the above it will be seen that it is possible to entirely disconnect any of the pontoons A or B that may have become 85 damaged or destroyed and replace the same without putting the dry dock entirely out of commission, and these changes may be made while the dock is still being used for the support or floating of a vessel or other 90 body that it may be desired to transport.

The pontoons will be provided at their upper part with one or more manhole covers 40 as may be desired to provide ready access into the interior of the pontoons or the compartments thereof.

In order to relieve the adjustment mechanism comprising the rack 10 and the screw 11 from the burden of the pressure as between the unit members, the transverse 100 girders or connecting elements 4 may ride in engagement with respective bearing portions 4' provided therefor in the longitudinal members or bridge work 3.

Various changes may be made without de- 105 parting from the spirit of my invention as claimed.

I claim:

1. A floating dry dock comprising two independent buoyant side units each having 110 a standing shore wall and a series of pontoons extending transversely from the respective units.

2. A floating dry dock comprising two independent buoyant side units each having a standing shore wall and a series of spaced 115 pontoons extending transversely to the unit to telescope between the pontoons of the other units.

3. A floating dry dock comprising two independent buoyant side units each having a standing shore wall and a series of spaced pontoons extending transversely to the unit to telescope between the pontoons of the other units, and means on each unit for air 120 charging the pontoons thereof.

4. A floating dry dock comprising two independent buoyant side units each having a standing shore wall and a power plant on one unit for relatively moving the units, 125

- when assembled, so as to accommodate vessels of different sizes.
5. A floating dry dock comprising two independent buoyant side units each having a standing shore wall and a series of spaced pontoons extending transversely to the unit to telescope between the pontoons of the other units, each pontoon independently removable from its unit.
- 10 6. A floating dry dock comprising two independent buoyant side units each having a standing shore wall, each unit having a rigid bridge, and keel engaging means on the pontoons.
7. A floating dry dock comprising two independent buoyant side units each having a standing shore wall, each unit having a rigid bridge, and keel engaging means on the pontoons and bearings between the relative units.

15 In testimony whereof I have signed my name to this specification.

20 ADRIEN C. BECKERT.
